UNITED STATES PATENT OFFICE.

ROBERT D. ANDREWS, OF BROOKLINE, MASSACHUSETTS.

AERIAL VEHICLE.

1,145,960.

Specification of Letters Patent. Patented July 13, 1915.

Application filed September 28, 1908. Serial No. 454,968.

To all whom it may concern:

Be it known that I, ROBERT D. ANDREWS, a citizen of the United States, a resident of Brookline, in the county of Norfolk and State of Massachusetts, have invented an Improvement in Aerial Vehicles, of which the following description, in connection with the accompanying drawings, is a specification, like letters on the drawings representing like parts.

My invention relates to aerial vehicles and more particularly to means for adjusting the relative positions of the supporting surfaces or sails thereon.

My invention comprises also adjusting means such that the vehicle may become automatically operative to maintain a given poise or stability thereby to eliminate what is at present a considerable source of accident.

My invention may be best understood by reference to the following description of one embodiment thereof, illustrated in the accompanying drawings wherein—

Figure 1 is a plan view of the vehicle having parts of the sails broken away; Fig. 2 is a side view thereof; Fig. 3 is a front view thereof; Fig. 4 is an enlarged detail showing an arrangement of frame joints and devices for adjusting the frame member; Fig. 5 is a section taken on line 5—5 of Fig. 4; Fig. 6 is an enlarged detail of devices for adjusting the sails; and Fig. 7 is a perspective view showing the vehicle in flight.

Referring to the drawings: My apparatus, as here shown comprises a central articulated frame supporting at one end suitable aeroplanes 1 and 2, and at the other end suitable aeroplanes 3 and 4. This central frame herein comprises a central triangular frame member ABC, and similar, but inverted fore and aft members ABE and ACD, hinged or otherwise adjustably connected obliquely to said central member on opposite edges thereof and along their adjacent oppositely inclined or oblique sides on lines X—X, Y—Y.

For the best results the fore and aft members ABE and ACD may be attached to the central members at any suitable angle such that the swinging of one or another of said

fore and aft members will lift a lateral portion of the supporting plane or sail carried thereby and depress another and opposite lateral portion thereof. The central member ABC is preferably constructed in the form of a truss, comprising a tie-beam BC, a king post AF and tie rods or guys AB and AC connecting the ends thereof. The member ABE which for convenience I will designate the fore member, although it may be constituted the aft member, is similarly constructed of a tie-beam AE and king post BG transverse thereto and suitable guys attached to the ends of said members. The aft member ACD also and similarly consists of a tie-beam AD a king post CH and guys connecting their free ends.

The fore and aft members ABE and ACD may be connected or hinged to the intermediate truss members ABC in any suitable manner. Herein the ends of the bars EA and AD adjacent to the top of the king post are provided with eyes 5 linked into a metallic eye 6 (Figs. 4 and 5) attached to the end of the king post AF. The eyes 5 may be conveniently attached to the tie bars EA and AD by notching the latter at their ends to receive a wire 7 which is given a twist at its end to form said eyes 5. The ends of each of these members may be served with wire 8, in order to strengthen the same. The above connection permits the axial lines of the bars EA, AD and AF to converge to a point A, and the guy AB acts as an element of both the central member and the fore member, while the guy AC acts as an element of both the central member and the aft member.

The typical hinge just described is employed also at B and C. The eyes 5 and 6 are of sufficient size to readily permit the attachment of guy wires or rods therein. It will be observed that the structure formed by the tie rods and their king posts, guyed in this manner affords a truss which is extremely rigid and, at the same time, is perfectly free to turn about the lines X—X, Y—Y.

The aeroplanes 1, 2, 3 and 4 for supporting the vehicle in the air, are similar in structure and may be attached to horizontal

shafts 14 on the ends of the fore and aft members ABE and ACD respectively. One or more aeroplanes may be used on each end of the vehicle, but herein two superposed 5 planes are shown offset from the vertical to give more effective support. These aeroplanes or sails herein may be supported upon frames 9 comprising members or spokes 10 and 11, of different length having guys 12 10 connecting their ends and enlarged at their crossing point to form hubs 13 to rotate on the ends of the shafts 14, and may be held in place by suitable pins 15. The shafts 14 are held perpendicularly to the fore and aft 15 members by suitable guys 17 and 18 extending from the ends of said shafts to the points A and B.

The sails may be conveniently and removably attached to the frames 9 by spars 19 20 slipped into loops in the sail edges and in eyes 20 in the ends of said spokes 10 and 11, and held by the suitable set screws 20'. The sail material will be of sufficient width to concave or belly slightly when mounted on 25 the frame 9. To further support the sails and maintain them in position, the spars 19 of the upper and lower planes may be connected by upright rods 21 spaced at intervals and having eyes in their ends similar to 30 those in the spokes 10 and 11 and with guys may be used as required to gain stiffness.

It will be apparent that the rotation of the frames 9 about the shafts 14 will enable the aeroplanes to be adjusted to any angle 35 with respect to the wind. This adjustment may be controlled by suitable steering ropes 22, 23 herein attached to the upper, inner ends of the spokes 11, passed around guide sheaves 24 downwardly around guide sheaves 40 25 fastened to the tie bar BC and then attached to the lower inner ends of the spokes 10. To rotate the sail as a whole about the shaft 14, the steering ropes 22, 23 may be operated in unison and thus cause the vehicle 45 to rise or fall.

A wide range of sail adjustment may be obtained by drawing on the ropes 22, 23 independently to warp the sail. In other words the forward edge portion of the sail 50 may be moved above or below the normal position of the aeroplane while the corresponding portion of the sail on the other side of the vehicle may be held stationary or given a reverse movement. To actuate and 55 hold the sails in these positions of adjustment the steering ropes 22, 23 may be passed a number of turns about the steering spools 26 and 27 (Fig. 6), the latter herein being loosely mounted on a shaft 28 supported in 60 a bearing 29 on the tie bar BC. These spools may be provided on one end with hand wheels 30, 31 integral therewith and on the other end with oppositely placed bevel gears 32, 33. The latter are pressed by springs 34,

35 to normally mesh with an intermediate 65 gear 36, mounted on a pin 37 extending from the bearing 29. The springs 34, 35 are interposed between the hubs of the hand wheels 30, 31 and enlargements 38, 39 at the ends of said shaft. If it is desired to rotate the sail 70 frames in unison about the shaft 14 the spools 26, 27 may be rotated together by either wheel 30 or 31 to pull the ropes 22, 23. The latter are led on to the spools 26, 27 at their opposite sides (Fig. 4) to compensate 75 for the opposite direction of rotation of said spools due to the drive through the intermediate gear 36. The sails may be warped by pulling out either hand wheel against the resistance of its spring thus withdrawing its 80 bevel gear from mesh with the intermediate gear 36 (Fig. 6) whereupon one spool may be rotated without affecting the position of the other spool. The hand wheel may be then released and springs 34, 35 will cause 85 the bevel gears to reengage. Said spools may be held in their positions of adjustment by a dog 40 weighted to remain normally in engagement with a toothed wheel 41 integral with the bevel gear 36. The aeroplanes 3 90 and 4, on the opposite end of the vehicle, are controlled in a similar manner.

To strengthen the central frame member ABC a horizontal laterally extending bar 42 may cross the king post AF transverse to the 95 longitudinal line of the vehicle at a point midway between the ends of said post. This bar 42 may be strengthened by means of guys extending from the ends of said bar 42 to the extremities of said king post. To 100 swing the aeroplanes 1-2, and 3-4 laterally about the lines X-X, Y-Y, suitable steering ropes 43 may be attached preferably to the ends of the shafts 14, brought toward each other, guided over sheaves 44 mounted 105 on the same pivot pin and located at the ends of the bar 42. Said ropes may be then passed a number of turns around a controlling winch 45, and attached to the other ends of the shafts 14. These ropes 43 act not only 110 to steer the vehicle but also as guys essential to the rigidity of the structure. The winch 45 is preferably placed parallel with the king post AF and is mounted on a suitable shaft, and may be controlled by a hand 115 wheel 46 located in any convenient position. The latter may be provided with teeth 47 on the inner face thereof and be held in adjusted position by means of any suitable dog 48. The steering ropes 43 are passed 120 preferably parallel to the bar 42, and while both shafts 14 are shown herein as controlled simultaneously by the winch 45 and hand wheel 46, they might be controlled separately by any suitable means as desired. 125

The bar 42 is rigid with respect to the central member ABC and therefore any movement of the latter is shared by said

bar. It may be supposed that the fore and aft members are swung about the central member. This will depress one end of the shafts 14 and raise the other at the same time raising one end of the steering rope 43 attached thereto and lowering the other. One end of the bar 42 will then be above the level of the depressed end of the shafts 14 and the other end of bar 42 will be below the raised end of the said shafts 14, and will thus compensate for the tilting of the latter, take up slack and keep the ropes 43 always taut. This is a necessary condition since said rope 43 is an essential element to maintain the rigidity of the apparatus. To steer the vehicle laterally the winch 45 may be rotated by the hand wheel 46 thus deviating the aeroplanes supported on the ends of the shafts 14, and moving the three frame members ABC, AEB and ACD away from their normal position in one plane. The whole or any part of the space defined by the guys of the trusses ABE and ACD may be filled with any suitable sail material, and herein the spaces HCD and GEB are shown so filled. It will be apparent that the vehicle may act as a glider or it may be provided with suitable engines 50 and propellers 51 herein mounted on the frame, at a proper distance from the king post AF.

In aerial vehicles of the aeroplane type it is necessary to provide some means to permit the vehicle to run along the ground in order to get up a speed sufficient to lift it into the air. To support the vehicle when on the ground any suitable wheels 52 may be mounted beneath the same and herein bicycle wheels are shown, attached to the king posts GB and HC of the fore and aft truss members, and therefore share their motion. These wheels 52 may be mounted in any suitable manner as by forks 53 which may be fixed to the said ribs, and their attachment strengthened by braces 54. The supported elements, such as the engine, passengers, or other load, may be carried by the intermediate member ABC and the vehicle controlled therefrom. Preferably the fore, aft and central members when in their normal relation will be in one and the same plane. When forced out of this normal relation the supported load will tend to return said members to their normal position in one plane, and in passing through the air the vertical sails in the fore and aft members will act as vanes and, when free to adjust themselves relatively to the central member, will automatically tend to assume positions in said normal plane, and keep the sails in position to support the vehicle. When these three members are not in one plane they will serve to change the course of the vehicle in a sidelong direction, the direction taken being toward that side ren-

dered concave by the position of said members.

In view of the fact that the sails or aeroplanes herein are attached at right angles to the planes of the fore and aft members respectively, the plane of the supporting sails of the vehicle will vary simultaneously with the variation of the truss members from a position in one plane. Since the latter variation is proportionate to the degree of concavity of the members, the sails will depart from a horizontal or normal position in proportion as the members are rendered concave and the course of the vehicle is changed, the effect being to raise the outer ends of the sails and to depress the inner ends. The guys and pliable sail supporting spars give the vehicle sufficient elasticity to yield to vagaries of air and at the same time give sufficient strength to hold the frame members in proper relation.

It is to be understood that my invention is not limited to the specific embodiment herein shown but that various modifications may be made without departing from the spirit of my invention.

Claims:

1. An apparatus of the class described comprising in combination, fore and aft main supporting surfaces, and connecting means therefor comprising adjustably connected members having provision causing them to tend to remain normally in one plane.

2. An aerial vehicle comprising, in combination, fore, aft and intermediate frame members adjustably connected one to another and normally in a continuous vertical plane, and main supporting aeroplanes carried by said fore and aft members.

3. An aerial vehicle comprising, in combination, fore and aft members and an intermediate member adjustably connected thereto, said members normally being in a continuous substantially vertical plane, means to vary the relation of said members at will, and main supporting aeroplanes carried by said fore and aft members.

4. An apparatus of the class described comprising in combination, fore and aft main supporting surfaces, and relatively adjustable members connecting said surfaces and having provision for automatically causing said surfaces to tend to remain in a given normal relation.

5. In an apparatus of the class described, the combination of a jointed frame having fore and aft sail carrying members, an intermediate member pivotally connected to said fore and aft members, and sails attached to the latter to share their motion, said members tending in flight to return to their normal position in a vertical plane.

6. An aerial vehicle comprising, in com-

- bination, an articulated substantially vertical main supporting frame having fore and aft aeroplane supporting members and an intermediate member hinged thereto, and means for moving said members with relation to each other.
7. An aerial vehicle comprising, in combination, an articulated main supporting frame having fore and aft members and an intermediate member hinged thereto, aeroplane supporting frames rotatably mounted on said fore and aft members and means for rotating said frames independently of each other.
- 10 8. In an apparatus of the class described, the combination of an articulated main supporting frame, sail carrying means rotatably mounted thereon and sails removably mounted on said carrying means.
- 15 9. An aerial vehicle comprising, in combination, an articulated body frame having normally vertical fore and aft sail carrying members and an intermediate load-carrying member.
- 20 10. An aerial vehicle comprising, in combination, a frame having normally vertical fore and aft main supporting surface carrying members and an intermediate member jointed to said fore and aft members respectively.
- 25 11. In an apparatus of the class described, the combination of a jointed frame having fore and aft sail carrying members and an intermediate member jointed obliquely to said fore and aft members respectively.
- 30 12. In an apparatus of the class described the combination of an articulated main supporting frame comprising a plurality of members, and aeroplane carrying means rotatably mounted on some of said members.
- 35 13. An aerial vehicle comprising, in combination, a main supporting frame having fore and aft members and an intermediate member adjustably connected thereto, and aeroplane carrying means rotatably mounted on said fore and aft members respectively.
- 40 14. An aerial vehicle comprising, in combination, a main supporting frame having rigid fore and aft members and a rigid intermediate member adjustably connected thereto, shafts mounted on and transverse to said fore and aft members, and aeroplane carrying frames rotatably mounted on said shafts.
- 45 15. In an apparatus of the class described, the combination of a frame having fore and aft sail-carrying members and an intermediate member and oppositely inclined connections between said fore and aft members and said intermediate member to permit relative adjustment of said members.
- 50 16. An apparatus of the class described comprising, in combination, a jointed frame having fore and aft members and an intermediate member, each comprising a longitudi-
- dinal tie-bar and a king post perpendicular thereto and guys passing from the ends of said longitudinal bar to the outer end of said post to form a rigid frame, said fore and aft members being inverted with respect to said intermediate member and adjustably attached thereto.
- 55 17. An apparatus of the class described having in combination a frame comprising normally vertical fore and aft members and an intermediate member adjustably attached thereto, main supporting surfaces attached to said fore and aft members, said surfaces and their supporting members moving together.
- 60 18. An aerial vehicle comprising in combination, an articulated normally vertical frame having fore and aft members and an intermediate load-carrying member and supporting surfaces attached to said fore and aft members.
- 65 19. An aerial vehicle comprising, in combination, a main supporting frame having fore and aft members, and an intermediate member adjustably attached thereto, sail-carrying frames adjustably mounted on said fore and aft members respectively, and sails removably mounted on said frames.
- 70 20. An aerial vehicle comprising, in combination, a jointed frame having fore and aft sail-carrying members, and an intermediate load-carrying member, horizontal shafts at the ends of said fore and aft members, sail-supporting frames mounted on the outer ends of said shafts, and means for rotating the frames on one shaft independently of each other to warp the sails.
- 75 21. In an aerial vehicle, the combination of a frame having fore and aft members and an intermediate member, said fore and aft members carrying main supporting surfaces and vertical sails.
- 80 22. In an aerial vehicle, the combination of a jointed frame having fore and aft members and an intermediate member obliquely and adjustably attached at its opposite ends to said fore and aft members, the latter carrying vertical and horizontal sails.
- 85 23. An aerial vehicle comprising, in combination, fore and aft members and an intermediate member hinged thereto, shafts rigidly attached to the outer ends of said fore and aft members respectively, sail frames rotatably mounted on said shafts, and sails on said frames, any movement of said fore and aft members being shared by said sails.
- 90 24. An aerial vehicle comprising, in combination, a main frame having fore and aft members and an intermediate member fulcrumed to said members, and means for changing the relation of said members to concave the frame as a whole to vary the direction of the vehicle.
- 95 25. An aerial vehicle comprising, in combi-

- nation, a jointed frame having fore and aft members and an intermediate member, the latter comprising a central vertical king post member, a tie-bar member perpendicular thereto at the base thereof, and a horizontal member perpendicular thereto and attached centrally thereon transverse to the line of travel of the vehicle, and propellers mounted thereon to drive the latter through the air.
26. In a device of the class described, the combination of fore and aft members and an intermediate member, horizontal means mounted on the outer ends of said fore and aft members respectively, and main supporting frames removably mounted on said means.
27. An aerial vehicle comprising, in combination, an articulated main supporting frame having fore and aft aeroplane supporting members and an intermediate normally vertical frame member adjustably attached at its ends to said fore and aft members respectively, means for moving said members with relation to each other, and means for holding them in their adjusted position.
28. In a device of the class described, the combination of a frame having fore and aft members and an intermediate load-carrying member jointed to said members, main supporting surfaces, frames therefor rotatably mounted on said fore and aft members, means for rotating said frames to bring the surfaces into varying angles, and means for holding said frames in position.
29. A device of the class described comprising, in combination, a frame having fore and aft members supporting a plurality of superposed aeroplanes, an intermediate member adjustably connected to said fore and aft members, and controlling means connecting said fore and aft members with said intermediate member, the latter serving as a position for controlling the vehicle.
30. An aerial vehicle comprising in combination, an articulated main frame, frames mounted rotatably thereon, aeroplanes mounted on the latter and adjustable therewith to present varying angles of incidence with respect to the wind, and means attached to said aeroplanes for adjusting them independently.
31. An aerial vehicle comprising, in combination, fore and aft members, an intermediate member, and steering means connected to said fore and aft members to move them similarly and simultaneously, said members being arranged normally to assume a position in a continuous vertical plane.
32. An aerial vehicle comprising, in combination, fore and aft members, an intermediate member fulcrumed thereto, sail supporting shafts transverse to and mounted on said fore and aft members, steering lines connected to the ends of the shafts on the
- fore and aft members, and means on said intermediate member to control said lines simultaneously.
33. An aerial vehicle comprising, in combination, fore and aft members, an intermediate member adjustably connected thereto, steering lines to control said fore and aft members and a truss bar extending laterally from said intermediate member to receive and guide said steering lines and take up any slack therein caused by the relative movements of said members.
34. In an apparatus of the class described, the combination of a frame having fore and aft sail-carrying members and an intermediate member and oppositely inclined connections between said fore and aft members and said intermediate member, said connections being in the same plane and permitting relative adjustments of said members.
35. In a flying apparatus, the combination of fore and aft aeroplanes and a frame connecting the same, members of which are connected to said aeroplanes and pivotally connected to an intermediate member on diagonal lines so that a load on the intermediate member tends to cause the aeroplanes to assume a normal position.
36. An aerial vehicle comprising, in combination, fore, aft and intermediate members obliquely and adjustably connected one to another to cause them automatically to tend to return to their normal positions in a continuous vertical plane.
37. An aerial vehicle comprising, in combination, fore and aft aeroplane members and an intermediate normally vertical frame member having upwardly converging jointed connections with said fore and aft members.
38. In an aerial vehicle the combination of a jointed frame comprising fore and aft sail-carrying truss members and an intermediate load-carrying truss member, said members being normally in the same plane.
39. In an aerial vehicle, the combination of main supporting surfaces with a jointed frame connecting said surfaces and comprising fore and aft truss members and an intermediate load carrying member, said members having provision inherent thereto for causing them to tend to remain in a normal position.
40. In an aerial vehicle the combination of a jointed frame comprising fore and aft sail-carrying truss members ABE, ACD, and an intermediate load-carrying truss member ABC, said members being normally in the same plane.
41. An aerial vehicle comprising, in combination, fore and aft spaced aeroplanes and an obliquely articulated frame therefor extending from one to another and supporting the same.
42. An aerial vehicle comprising, in com-

bination, fore and aft spaced aeroplanes and a supporting frame therefor extending from one to the other and having a transverse joint extending obliquely to the longitudinal axis of said frame.

- 5 43. An aerial vehicle comprising, in combination, fore and aft spaced aeroplanes and a supporting frame therefor provided with diagonal joints extending along downwardly divergent axes transverse to the longitudinal axis of the frame, said joints permitting the turning of the aeroplane whereby the latter are changed from their 10 normal positions to one in which they assume the relation of the sides of a pyramid having its apex downward.

- 15 44. In an aerial vehicle the combination of two aeroplanes substantially at the same level and separated in a fore and aft direction with a structural member supporting said aeroplanes, said member being jointed obliquely to its longitudinal axis and in the vertical plane of the vehicle, the whole presenting a symmetrical construction permitting 20 the vehicle to be driven in either direction.

- 25 45. In an aerial vehicle the combination of fore and aft spaced aeroplanes with a supporting frame therefor jointed obliquely to the longitudinal axis of said frame and means for concavaging said frame whereby to 30 change the course of the vehicle.

46. An aerial vehicle comprising, in com-

bination, fore and aft spaced aeroplanes, a main longitudinal truss frame therefor comprising a plurality of rigid parts normally in a vertical plane and adjustably connected along upwardly converging axes.

35

47. An aerial vehicle comprising, in combination, fore and aft spaced aeroplanes and a longitudinal supporting frame therefor, symmetrical in a fore and aft direction comprising a plurality of parts adjustably connected along upwardly converging axes, means on said frame for varying the angles 40 of said aeroplanes to the wind, the latter being similar in shape and area, but opposite in fore and aft conformation permitting the vehicle to be propelled with equal facility in either a fore or aft direction.

45

50

48. In a flying apparatus, the combination of a frame with fore and aft main supporting surfaces hinged thereto permitting the variation of the angles of incidence of said surfaces, said frame having provision permitting the adjustment of the portions of 55 said main fore and aft surfaces located on one side of the apparatus toward or from one another.

55

In testimony whereof, I have signed my name to this specification in the presence of two subscribing witnesses.
